(57) **CLAIM**

The design for the lightning arrester, as shown.

DESCRIPTION

FIG. 1 is a perspective view of the lightning arrester according to the present invention;

FIG. 2 is a front elevational view of the lightning arrester according to the present invention;

FIG. 3 is a rear elevational view of the lightning arrester according to the present invention;

FIG. 4 is a left side elevational view of the lightning arrester according to the present invention;

FIG. 5 is a right side elevational view of the lightning arrester according to the present invention.

FIG. 6 is a top plan view of the lightning arrester according to the present invention; and,

FIG. 7 is an underside plan view of the lightning arrester according to the present invention.

1 Claim, 6 Drawing Sheets
